No. 822,173.

PATENTED MAY 29, 1906.

J. A. WILSON,
STORM FRONT FOR BUGGIES.
APPLICATION FILED MAY 26, 1905.

UNITED STATES PATENT OFFICE.

JOHN A. WILSON, OF GEORGETOWN, OHIO, ASSIGNOR, BY MESNE ASSIGNMENTS, OF ONE-HALF TO LORA DUNN WILSON, OF GEORGETOWN, OHIO.

STORM-FRONT FOR BUGGIES.

No. 822,173.

Specification of Letters Patent.

Patented May 29, 1906.

Application filed May 26, 1905. Serial No. 262,449.

To all whom it may concern:

Be it known that I, JOHN A. WILSON, a citizen of the United States, residing at Georgetown, in the county of Brown and State of Ohio, have invented a new and useful Improvement in Storm-Fronts or Aprons for Buggies, of which the following is a specification.

This invention relates generally to storm-fronts or aprons for carriages, and more particularly to one adapted to be attached to the folding carriage or buggy top.

The object of the invention is to provide a storm-front with such appliances that it can be attached and detached quickly and easily; and a still further object is to provide fastening appliances of such a character that when the storm-front is connected all danger of working loose at the top, bottom, or sides is entirely avoided.

With these various objects in view my invention consists in the novel features of construction hereinafter fully described, and pointed out in the claim.

In the drawings forming a part of this specification, Figure 1 is a view showing the practical application of my invention. Fig. 2 is an interior view showing the manner of connecting the lower portion of the storm-front to the dashboard of the vehicle. Fig. 3 is a front elevation of the buggy-top with the storm-front-attaching means shown in section. Figs. 4 and 5 show details of the connecting means. Fig. 6 is a detail section on the line 6-6 of Fig. 3. Fig. 7 is a view showing the manner of connecting the side of the apron or front to the upright of the top. Figs. 8 and 9 are detail views of the spring-clasp.

Referring to the drawings, A indicates the carriage-body, and B the top thereof, and C is the storm-front or apron, which is so shaped as to extend from the front of the top over the dashboard and along the side from the dashboard to the sides of the top or cover, as most clearly shown in Fig. 1.

For the purpose of connecting the upper portion of the storm-front or apron to the top of the buggy and in such a manner that it can be quickly and easily attached and detached from within the carriage or buggy I employ a strap D, which is connected to the edge of the storm-front or apron, and this strap is preferably enveloped in a hem of the

apron, as most clearly shown at C' in Fig. 6, 55 and is secured by a line of stitching or in any other suitable manner. This strap D does not extend to the side edges of the apron, but stops some distance short of said edges, and connected to the ends of the strap are the 60 coil-springs E, said coil-springs being enveloped in the hem, and at their outer ends they have the depending hooks F loosely connected thereto, and each hook has a hand-strap G fastened thereto, by means of which 65 the hooks F can be pulled down and brought into engagement with the top joints of the carriage-top, it being understood that the hand-straps G extend down between the carriage-cover and the storm-front or apron, 70 so as to be within convenient reach of the person within the carriage. After the hooks have once been brought into engagement with the top joint the top portion of the apron or storm-front will be tightly held to 75 the carriage-top and all danger of displacement entirely avoided.

For the purpose of fastening the lower portion of the apron or front I employ two straps H, connected to the interior of the apron adjacent the lower end thereof and provided with a buckle H', by means of which they can be fastened upon the inner side of the dashboard, the apron or storm-front extending over the dashboard, as most clearly 80 shown in Figs. 1 and 2, and for the purpose of preventing the lower end of the apron or front riding up on the dashboard I employ a strap I, having a hook K at its lower end, which is adapted to engage the foot-rail L, 85 the upper end of the strap I being fastened to one of the straps H adjacent its inner end. The apron is also provided at each side with a strap M, which carries at its rear end a spring-clasp N, preferably made of a single 90 piece of wire and comprising two jaws and a central coil, said clasp being adapted to engage the bow-sockets near their lower ends, and thereby hold the sides of the apron or front in their proper position, the spring- 95 jaws of the clasp embracing and holding fast the bow-sockets; but it will be understood that when it is desired to disengage the apron or front a quick pull will serve to disengage the clasps. It will also be understood that 100 in order to disengage the top it is only necessary to pull down upon the hand-straps G and throw the hooks F out of engagement 105

with the top joints. The front can then be detached from the dashboard and folded up and packed away.

It will thus be seen that I provide an exceedingly simple and efficient means for securing the storm-front or apron to the top and dashboard of the vehicle, said means being of such a construction that the attachment and detachment can be made very easily and in a very short space of time.

Having thus fully described my invention, what I claim as new, and desire to secure by Letters Patent, is—

A storm-front for buggies comprising an apron provided with straps connected to-

gether by a buckle, a strap connected to said buckle-strap provided with a hook at its free end, a strap enveloped in a hem formed along the upper edge of the apron, said strap terminating short of the side edges of the apron, carrying coil-springs at its end within the hem, hooks loosely connected to the ends of said springs, hand-straps connected to the free ends of said hooks, and straps carried by each side of the apron provided with spring-
20 clasps, for the purpose set forth.

JOHN A. WILSON.
